CLAIM

The ornamental design for a table lamp, as shown and described.

DESCRIPTION

1.1 is a front perspective view of a table lamp, showing my new design;

1.2 is a front view;

1.3 is a rear view;

1.4 is a left side view;

1.5 is a right side view;

1.6 is top view; and

1.7 is a bottom view.

The broken lines shown in the drawings of the table lamp are for the purpose of illustrating the environment and form no part of the claimed design.
